(57) **CLAIM**

The ornamental design for a plant lamp, as shown and described.

DESCRIPTION

FIG. 1 is a front and bottom perspective view of a plant lamp, showing my new design;

FIG. 2 is a rear and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged perspective view of detail "9" identified in FIG. 1;

FIG. 10 is an enlarged perspective view of detail "10" identified in FIG. 2;

FIG. 11 is an enlarged perspective view of detail "11" identified in FIG. 2;

FIG. 12 is an enlarged perspective view of detail "12" identified in FIG. 3; and,

FIG. 13 is an enlarged perspective view of detail "13" identified in FIG. 7.

The dashed lines in the figures illustrate portions of the plant lamp that form no part of the claimed design. The dash dot dash lines in FIGS. 1, 2, 3, 7, 9, 10, 11, 12 and 13 are for the purpose of illustrating the enlarged portions and form no part of the claimed design.

1 Claim, 13 Drawing Sheets
